UNITED STATES PATENT OFFICE.

CARL AUGUST PFENNING, OF BARMEN-RITTERSHAUSEN, GERMANY, AS-SIGNOR TO WALTER LUCKHAUS, OF BARMEN-RITTERSHAUSEN, GERMANY.

FASTENER FOR BOOTS, &c.

SPECIFICATION forming part of Letters Patent No. 715,858, dated December 16, 1902.

Application filed June 10, 1902. Serial No. 111,033. (No model.)

To all whom it may concern:

Be it known that I, CARL AUGUST PFENNING, a subject of the Emperor of Germany, residing at Barmen-Rittershausen, Germany, 5 have invented new and useful Improvements in Fasteners for Boots and the Like, of which the following is a specification.

My invention relates to fasteners having a hollow top capable of being pressed down upon and held by a stud. When such fasteners are applied to foot-gear, it is necessary that the stud be of minimum height and that the top be held by the stud immediately above the disk or base of the latter; otherwise the 15 part will tilt and exercise a disturbing pressure on the foot of the wearer. In practice, however, it is difficult to manufacture effective fasteners with such a low stud, since the tension, especially in new shoes, of the leather 20 or other material of the uppers renders it almost impossible by simple pressure with the hand to bring the top down upon the stud in the correct position to unite the parts—that is, to fasten the shoe. For the purpose of 25 overcoming this defect I provide on the disk of the stud a suitably-formed projecting part, which lies beyond the edge of the fastener-top. Such projecting part affords a hold to the finger and also renders possible the em- 30 ployment of a buttoner for fasteners with low stud, inasmuch as the projecting part referred to presents a point of support for the buttoner.

The appended drawings illustrate my new 35 fastener drawn to a much enlarged scale.

Figure 1 is an elevation of the top part of the fastener applied to a portion of the boot-upper. Fig. 1^a is a like view of the stud part similarly applied. Fig. 2 is a plan view of the 40 stud part. Fig. 3 is a view illustrating the application of a buttoner for the purpose of closing the fastening; and Fig. 3^a is a plan view of the top part as shown in Fig. 3. Fig. 4 illustrates the application of a buttoner to 45 a modified construction of the stud portion of the fastener.

a is the disk or base of the stud *b* and is

provided with a projecting part *c*, preferably formed by making the disk with a lip or lug *m*, which is then bent over into the desired 50 shape. The distance of the part *c* from the stud must be so great that the top *d* on being pressed down upon the stud is not prevented from lying closely against the disk. This projection *c* affords a hold for the finger, 55 whereby the stud part of the fastening can be drawn toward the top part, while the latter, on account of its size and of its projecting free above the leather, can be sufficiently grasped with the other finger to bring it over 60 the stub *b*. The latter remains in quite free position, so that the top part in engaging the stud is no way obstructed by the finger which is applied to the projection *c*. The buttoner for such a fastener consists of two shanks *g* *h*, 65 linked together by a member *f*. In applying such buttoner the projection *c* serves as support for the one shank *h* (see Fig. 3) when the turned-over end of the other shank *g* seizes the top *d*. Hitherto the top *d* has had 70 to be made higher than the stud *b* by an amount equal to the thickness of the shank *h*, since otherwise the top *d* does not sufficiently grip over the stud. The consequence is that the top does not tightly fit against the 75 stud after removal of the buttoner, and owing to the pull upon the upper end of the stud during wear the stud portion will tilt and press into the foot of the wearer. By means of the projection *c*, however, a buttoner can 80 be employed also for fasteners with flat or low stud, which, as already stated, is the only kind suitable for foot-gear.

If the projecting part *c* is so bent as to form a ridge *m*, gripping into the leather, the stud 85 part will be held all the firmer in place, since it will be prevented from turning.

The part *c* can, if desired, be bent as shown in Fig. 4, whereby the shank *h* of the buttoner can be introduced below the front edge of the 90 lug *c*, so as to butt against the ridge *m*, which will prevent it from advancing farther and coming under the stud-base, so loosening the parts. The buttoner according to this ar-

rangement will slightly raise the stud, so bringing it into a most favorable position for entering the hollow top *d*.

Having thus described my invention, I claim as new—

A stud portion for a fastener of the kind described, having a projecting portion provided with lugs upon its upper and lower faces, and the outer face of the upper lug being substan-

tially at a right angle to said projecting portion, substantially as described.

In testimony whereof I have hereunto set my hand in the presence of two subscribing witnesses.

CARL AUGUST PFENNING.
